UNITED STATES PATENT OFFICE.

CLARKSON S. FRENCH, OF SALEM, OHIO.

WIRE HOLDER AND INSULATOR.

1,168,796.

Specification of Letters Patent. Patented Jan. 18, 1916.

Application filed September 5, 1912. Serial No. 718,610.

To all whom it may concern:

Be it known that I, CLARKSON S. FRENCH, a citizen of the United States, residing at Salem, in the county of Columbiana and State of Ohio, have invented a certain new and useful Wire Holder and Insulator, of which the following is a specification.

My invention relates to improvements in wire holders and insulators and has for its object to provide an improved wire holder and insulator in which it is not necessary to wrap the wire around the insulator and in which the tying of the wire to the insulator is unnecessary.

15 A further object is to provide a wire holder and insulator in which the wire is more quickly and tightly clamped in position than by the ordinary construction.

These objects, together with other objects 20 readily apparent to those skilled in the art I attain by the construction illustrated in the accompanying drawings, although my invention may be embodied in a variety of other mechanical forms, the construction 25 illustrated being chosen by way of example.

Figure 1 of the drawings is a vertical section partly in elevation of my improved wire holder and insulator. Fig. 2 is a side elevation of the same. Fig. 3 is a front elevation 30 of the same with parts broken away to show the wire. Fig. 4 is a section on line 4—4, Fig. 3.

Similar numerals of reference indicate 35 corresponding parts throughout the several views.

The insulator comprises the outer hollow member 1, adapted to fit over the inner member as shown in Fig. 1. The member 2 is provided with a groove 3 to accommodate 40 the wire 4 and is substantially the same in form as the ordinary insulator now in use. The outer member 1 is provided upon either side with an inclined slot 5 having the enlarged portion 6 at its upper extremity. As 45 shown in Fig. 4 the wire passes through one of the slots 5 around the groove 3 and through the other slot 5. It will thus be

seen that the wire is held in an arc inside of the insulator thus causing it to be tightly gripped. As the wire lies in the enlarged portion 6 of the slot and as the slot is inclined away from the center of the outer member 1 the wire is held firmly in place and there is no chance of its working its way out of the slots 5. A flange 7 is provided 50 around each of the slots 5 so that water dropping upon the flange will be carried down and will drip off of the lower extremity of the member 1 and not pass into the slots 5.

55 In order to clamp the wire upon my wire holder and insulator, the wire is first laid against one side of the groove 3 in the member 2. The outer member 1 is then fixed down over the top of the member 2, the slots 5 engaging the wire 4 and as said member 1 is brought into place the wire will assume 60 the position shown in Fig. 4.

65 The insulator is made of any suitable insulating material preferably porcelain.

70 I claim—

In a wire holder and insulator, the combination of outer and inner members, said outer member formed hollow and adapted to fit over and upon the inner member, said inner member provided with an annular groove and said outer member provided with slots, said slots being inclined toward each other at their lower extremities, the upper ends of said slots terminating in wire retaining recesses disposed toward each other, said recesses being so located with relation to the periphery of the annular groove that a straight line drawn through both of said recesses would intersect the periphery of the 80 annular groove at a point adjacent each of the recesses.

85 In testimony that I claim the above, I have hereunto subscribed my name in the presence of two witnesses.

CLARKSON S. FRENCH.
